J. B. RUSS

BAG LOCK ESCUTCHEON OR SIMILAR ARTICLE

Filed Dec. 27, 1927

John B. Russ INVENTOR.

Bascom Lawrence ATTORNEYS.

UNITED STATES PATENT OFFICE.

JOHN B. RUSS, OF SHELTON, CONNECTICUT, ASSIGNOR TO THE BASSETT METAL GOODS COMPANY, INC., OF DERBY, CONNECTICUT, A CORPORATION OF CONNECTICUT.

DESIGN FOR A BAG-LOCK ESCUTCHEON OR SIMILAR ARTICLE.

Application filed December 27, 1927. Serial No. 24,651. Term of patent 7 years.

To all whom it may concern:

Be it known that I, JOHN B. RUSS, a citizen of the United States, residing at Shelton, county of Fairfield, State of Connecticut, have invented a new, original, and ornamental Design for a Bag-Lock Escutcheon or similar article, of which the following is a specification, reference being had to the accompanying drawing, forming a part thereof.

The drawing shows a perspective view of a bag lock escutcheon showing my new design.

I claim:

The ornamental design for a bag lock escutcheon or similar article as shown.

JOHN B. RUSS.
